UNITED STATES PATENT OFFICE.

THOMAS DAVITT, OF ATLANTA, GEORGIA.

WIRE TWISTING OR SPLICING MACHINE.

1,092,028.

Specification of Letters Patent. Patented Mar. 31, 1914.

Application filed April 8, 1913. Serial No. 759,701.

To all whom it may concern:

Be it known that I, THOMAS DAVITT, a citizen of the United States, residing at Atlanta, in the county of Fulton and State of Georgia, have invented new and useful Improvements in Wire Twisting or Splicing Machines, of which the following is a specification.

This invention relates to a machine for splicing or intertwisting the ends of wires, the object of the invention being to provide a machine of this character whereby the operation of splicing the ends of wires may be easily, conveniently and rapidly carried out and a permanently strong splice produced.

A further object of the invention is to provide a novel construction of twister shaft and twister head for machines of the character described, whereby simplicity and efficiency of action is secured.

The invention consists of the features of construction, combination and arrangement of parts hereinafter fully described and claimed, reference being had to the accompanying drawings, in which:—

Figure 1 is a side elevation of a wire splicing or twisting machine embodying my invention. Fig. 2 is an end elevation of the same. Fig. 3 is a top plan view of the machine. Figs. 4 and 5 are vertical transverse sections on the lines 4—4 and 5—5 of Fig. 1. Fig. 6 is a detail transverse section through one of the rocker arms, twister shaft and connecting parts. Fig. 7 is a perspective view of one of the twister shafts and its twister head. Figs. 8 and 9 are views illustrating the character of splice made.

Referring to the drawings, 1 designates a suitable base, from which rises a column 2 carrying a supporting frame 3. Journaled in suitable bearings on this frame is a transverse shaft 4, provided with a crank handle 5 or other means for applying power thereto. On this shaft is a spur driving pinion 6 meshing with a spur transmission gear 7 with transmission or countershaft 8, on which shaft 8 is also mounted an actuating cam 9.

Journaled in suitable bearings 10 on the frame, at opposite sides of the transverse center thereof, are longitudinally extending twister driving shafts 11 and 12, which carry at their inner ends bevel pinions 13 and 14 meshing with a bevel drive pinion 15 on the shaft 4, whereby said shafts 11 and

12 are adapted to be driven simultaneously in opposite directions at uniform rates of speed. The shafts 11 and 12 are also provided with spur gears 16 and 17, which in turn communicate motion to spur gears 18 and 19. The gears 18 and 19 are each provided with a radial slot 20^a, and supported by the frame and arranged to partially inclose each set of gears 16 and 18 and 17 and 19 are pairs of companion guards 20 and 21, the proximate upper edges of which are arranged to diverge, as at 22, to permit of the insertion and removal of the wires within and from the slots 20^a of the gears 18 and 19, and the slots in the coacting twister shafts and twister heads, as hereinafter fully described. The gears 18 and 19 are disposed between the parts of bifurcated bearings 23, in which are journaled longitudinally extending twister shafts 24 and 25, said shafts being slidably and rotatably mounted in said bearings, and each shaft having a longitudinally extending slot 26^a registering with the slot 20^a in the associated gear 18 or 19. Each twister shaft is also provided at its inner end with a longitudinally slotted twister head 26 provided with a twister hook 27, said head being secured to the shaft by a set screw 28. The gears 18 and 19 are held from longitudinal sliding movements with the twister shafts by the bifurcated bearings 23, but are feathered to the shafts for rotation therewith, so that when power is applied to rotate said gears 80 the twister shafts will be simultaneously rotated.

The cam 9 is provided with a recessed or depressed portion 29 and peripherally engages a friction roller 30 on a longitudinally movable actuating bar or lever 31. The opposite ends of this actuating bar or lever are pivotally connected with rocker arms 32 and 33 fulcrumed respectively to bracket members 34 and 35. The actuating bar is pivotally coupled to the rocker arm 32 at a point intermediate the length of the latter, said rocker arm 32 being pivotally connected at its lower end with the bracket 34, while the opposite end of the actuating bar is pivotally coupled to the lower end of the rocker arm 33, which is fulcrumed intermediate its length to the bracket 35, whereby when said actuating bar is moved longitudinally in either direction the upper ends of the rocker arms will be simultaneously moved in opposite directions. A coiled

spring 36 connects one end of the actuating bar to the frame 3 and maintains the actuating bar in normal or retracted position, in which position of said bar the friction roller 30 is engaged with the recessed portion of the cam and the twister shafts are disposed in retracted position.

The outer end of each twister shaft carries an annularly grooved slotted thrust collar 37, between the flanges of which are arranged diametrically disposed thrust blocks 38, which are pivotally mounted upon the upper fork ends of the rocker arms, whereby a proper longitudinal movement 10 may be imparted from each rocker arm to the associated twister shaft, while the rocker arm is permitted to swing in its prescribed arc, and at the same time the shaft is permitted to have rotary motion without interference from the rocker arm.

At a point centrally of the frame and between the respective twister heads is arranged an upright 39 supporting a wire clamping device embodying fixed and sliding clamping jaws 40 and 41, the jaw 41 being movable in and out by means of a screw shaft 42 provided with an actuating hand wheel 43.

In operation, assuming the parts of the apparatus to be in normal or receiving position, as illustrated in Fig. 1, the ends of the wire 44 and 45 are laid longitudinally in the slots of the twisters and between the jaws of the clamping device, the extremities of 35 the opposite wires being disposed to terminate in proximity to the hooks of the respective twisters so as to be engaged thereby. When the wires to be spliced are thus arranged, the hand wheel 43 is operated to 40 adjust the movable clamping jaw and clamp the wires at a point intermediate the points where the overlapping ends thereof are to be twisted or spliced, after which the crank 5 or other driving element is set into action. 45 The rotation of the crank wheel, it is evident, causes the shafts 11 and 12 to be simultaneously driven in opposite directions at uniform speeds, and motion to be transmitted therefrom to the twister shafts, 50 which will thus be rotated. At the same time the cam 9 will be actuated through the intervening gearing in the direction of the arrow shown in Fig. 1, thus actuating the rocker arms to move the twister shafts 55 inwardly. The twister shafts will thus be simultaneously rotated and moved inwardly until the twister hooks come in close proximity to the clamped portions of the wire, the hooks serving to engage and twist the 60 free ends of the wire in opposite directions about the body of the wire, thus splicing or intertwisting the ends of the wire firmly and securely together. The gearing between the main drive shaft and twister shafts and said 65 main drive shaft and the cam driving shaft

is so proportioned that the twister shafts are rapidly revolved during their entire inward motion, during which the wires are intertwined, which action is completed at the time the cam has made one complete revolution and the recessed portion thereof again comes into contact with the friction roller 29, whereupon the spring 36, which has been expanded by the forward motion of the actuating bar, contracts and restores 70 said bar to normal position, thus at the same time drawing the twister shafts outwardly to normal position, ready for a repetition 75 of the operation above described. On the restoration of the twister shafts to normal position, the slots therein are again upwardly disposed, so that the spliced wires 80 may be lifted out and new wires inserted to be spliced together.

It will be seen from the foregoing description 85 that my invention provides a wire splicing or twisting device which is simple of construction, inexpensive of production, and adapted to be easily, conveniently and rapidly operated, and that in action the twister 90 hooks as they feed along the wire will twist the free ends of the wire closely and compactly about the body of the wire, thus forming a permanently secure splice.

I claim:—

1. In a wire splicing machine, the combination of a wire clamping device, longitudinally slotted twisters on opposite sides thereof, cam controlled mechanism for sliding said twisters toward and from said 100 clamping device, and gearing for actuating said cam mechanism and for rotating said twisters on their inward movement.

2. In a wire splicing machine, the combination of a wire clamping means, longitudinally slotted, slideable and rotary twisters on opposite sides thereof, rocker arms for sliding said twisters, a connection between said rocker arms, cam mechanism acting on said connection for sliding the twisters, inwardly, and gearing for actuating said cam mechanism and simultaneously rotating said twisters.

3. In a wire splicing machine, the combination of a wire clamping device, longitudinally slotted slideable and rotatable twisters on opposite sides thereof, rocker arms for sliding said twisters, a connection between the rocker arms, spring means for holding and returning the rocker arms and twisters in normal position, cam mechanism acting on said connection for actuating the rocker arms to move the twisters inwardly, and gearing for operating said cam mechanism and imparting rotary motion to the 115 twisters.

4. In a wire splicing machine, the combination of a wire clamping device, longitudinally slotted rotary and sliding twisters on opposite sides thereof, gearing for simul- 130

- simultaneous inward and outward motion, and cam mechanism driven from said shaft and adapted to control said coupling means to slide the twisters inwardly and permit of 15 their retraction at timed intervals.
5. In a wire splicing machine, the combination of a wire clamping device, longitudinally slotted rotary and sliding twisters on opposite sides thereof, a drive shaft, gearing for rotating said twisters in opposite directions from said shaft, automatically retractable means coupling the twisters for
- In testimony whereof I affix my signature in presence of two witnesses.
